UNITED STATES PATENT OFFICE.

WILLIAM CLINTON SPEER, OF QUINAULT, WASHINGTON.

STRAIGHT-PULL BOLT-ACTION RIFLE.

Application filed July 21, 1925. Serial No. 45,041.

To all whom it may concern:

Be it known that I, WILLIAM CLINTON SPEER, a citizen of the United States, residing at Quinault, in the county of Grays Harbor and State of Washington, have invented certain new and useful Improvements in a Straight-Pull Bolt-Action Rifle, of which the following is a specification.

The present invention relates to a rifle and has for its principal object to provide a straight pull bolt action, whereby the cartridges from the magazine may be ejected and injected in relation to the firing chamber more quickly and easily than is possible with the rifles now in common use.

Another important object of the invention is to provide an improved locking mechanism for the rifle which will greatly enhance the safety thereof.

A still further important object of the invention is to generally improve upon rifles by providing an exceedingly simple construction, one which may be manufactured at a relatively low cost and yet will be strong, durable, efficient and reliable in operation, not likely to easily become out of order, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing—

Figure 1 is a fragmentary sectional elevation of the rifle embodying the features of my invention,

Fig. 2 is a top plan view of the bolt,

Fig. 3 is a sectional view taken through the juncture of the bolt and sleeve,

Fig. 4 is a transverse section through the sleeve of the bolt,

Fig. 5 is a transverse section through the magazine of the rifle.

Fig. 6 is a fragmentary elevation of the rifle, and

Fig. 7 is a detailed section taken transversely through one of the receiver bridges and the bolt.

Referring to the drawing in detail, it will be seen that 5 designates the stock of the rifle which may be of suitable design and is provided with the recess 6 for receiving

the magazine 7 having the follower 8 therein normally pushed upwardly by follower springs 9. As is shown particularly in Fig. 5, this magazine has an opening 10 at its top wall and one of the side walls is curved inwardly at the opening as is indicated at 11 so as to properly guide the cartridges which are disposed in staggered relation in the magazine, the bottom 1 thereof being engaged with a cleat 12 on the follower. The receiver is indicated generally by the letter A and includes the front and rear bridges 13 and 14 respectively connected by top walls 15.

A bolt 16 is slidable in the receiver for the purpose of holding a cartridge in the firing chamber of the barrel 17. This bolt is slidable for the ejection of a cartridge in the firing chamber and for receiving a cartridge from the magazine and placing the same in the firing chamber.

A sleeve 18 is detachably engaged with the rear or stock end of the bolt 16. This engagement is accomplished by providing the rear end of the bolt with an annular groove 19 engageable by the inner ends 20 of pivoted dogs 21 mounted in the barrel 18 and having their rear or outer ends projecting outwardly therefrom as is indicated to advantage in Fig. 4 so that by pressing these outer ends inwardly, the ends 20 may be disengaged from the annular groove 19 and thus the bolt 16 may be disassembled from the sleeve 18. Lugs 23 are mounted on the bolt 16 for movement in the slots 24, shown to advantage in Fig. 7, in the receiver bridges 14 so that in order to slide the bolt it must first be rotated. An ejector ring 25 is disposed in a suitable groove provided about the bolt 16 and mounts the ejector 26 longitudinally of said bolt.

As stated above, the principal object of the invention is to provide a straight pull bolt, that is, to provide a bolt wherein a straight pull first rotates the bolt to properly register the lugs 23 with the longitudinally extending portions of the bayonet slots 24 and to then pull the bolt for ejecting the cartridge in the firing chamber and allowing another cartridge to move upwardly from the magazine in order that when the bolt is pushed back, said latter mentioned cartridge will be pushed into the firing chamber. This straight pull is accomplished by providing an annular head

28 on the stock end of the bolt 16 and providing the same with cogs 29 for engagement with cogs 30 on a lever 31 pivoted as at 32 on the sleeve 18.

5 By referring particularly to Figs. 2 and 6 it will be seen that when the lever 21 is pulled toward the butt of the stock 5, the bolt will first be rotated until the lugs 23 reach the ends of the arcuate circumferential portions of the slots 24 and then will be pulled toward the butt, said lugs 23 moving through the straight longitudinal portions of the slots 24, thereby causing the ejection of the cartridge which may be 15 disposed in the firing chamber of the barrel 17 and allowing another cartridge from the magazine 7 to be disposed in front of the bolt so that when the bolt is pushed back again, said latter mentioned cartridge will 20 be pushed into the firing chamber of the barrel.

It will be understood, of course, that the ejector 26 is fixed to the sleeve 18 as is indicated at 34 in Fig. 2. The stock 5 is provided with the longitudinally extending groove 35 which forms a longitudinal branch of the lower bayonet slot 24 in the bridge 14 so that one of the lugs 23 will move therein when the bolt is being slid 30 in and out of the receiver.

The numeral 36 represents the cocking piece having a notch 37 at its top and a shoulder 38 at its bottom. A shaft 39 is rotatable through the sleeve 18 and has a 35 crank portion 40 intermediate its ends for engagement with the notch 37 to hold the cocking piece in a cocked position so that it cannot be released by the trigger mechanism which will be described later. On the 40 shaft there is provided a cam 41 engageable in the fork 42 of a lever 43 pivoted intermediate its end as at 44 and provided with an extension 45 which will be disposed in the path of movement of the arm 31 when 45 the crank 40 is engaged with the notch 37, thereby preventing the withdrawal of the bolt. The shaft 39 is rotatable by a crank 46 to one side of the sleeve 18. The sear 47 is pivoted as at 48 intermediate its ends 50 and is engageable with the shoulder 28, being normally held thus engaged by the sear spring 49. A set screw 50 is associated with the other end of the gear 47 for limiting the movement thereof as may be desired. 55 A link 51 is pivotally engaged with the sear 47 and also with a trigger 52 mounted in the usual manner in the stock so as to be movable in the guard 53. By the adjustment of the screw 50, the location of 60 the trigger 51 may be varied as desired.

It is thought that the construction, op-

eration, and advantages of this invention will now be clearly understood without a more detailed description thereof. It is desired, however, to point out that numerous 65 changes in the details of construction, and in the combination and arrangement of parts may be resorted to without departing from the spirit or scope of the invention as hereinafter claimed or sacrificing any of 70 its advantages.

Having thus described my invention, what I claim as new is:—

1. In a rifle of the class described, a stock, a receiver on the stock, a bolt rotatable and 75 slideable in the receiver, a head on the bolt provided with cogs, a sleeve slideable on the stock and engaged with the bolt, a lever pivotally mounted on the sleeve and having cogs meshed with the cogs of the head so 80 that a continuous swinging of the lever will cause the rotation of the bolt and the sliding thereof, means for engaging the sleeve with the head wherein the bolt is provided with an annular groove and a pair of 85 pivoted dogs are mounted in the sleeve and engageable with the groove.

2. In combination, a bolt, a sleeve associated with the bolt, a cocking piece associated with the bolt and movable in the 90 sleeve, said cocking piece including a shoulder and a notch, a trigger mechanism associated with the shoulder, a shaft rotatable in the sleeve and including a crank engageable with the notch for holding said cocking piece locked, means on the sleeve for rotating the bolt and sliding the bolt and sleeve.

3. In combination, a bolt, a sleeve associated with the bolt, a cocking piece associated with the bolt and movable in the 100 sleeve, said cocking piece including a shoulder and a notch, a trigger mechanism associated with the shoulder, a shaft rotatable in the sleeve and including a crank engageable with the notch for holding said cocking piece locked, means on the sleeve for 105 rotating the bolt and sliding the bolt and sleeve, said shaft provided with a cam, a lever pivoted in the sleeve and having a 110 forked end engageable with the cam and having its other end laterally disposed so that when said shaft is rotated to place said crank in engagement with said notch said cam will actuate the forked end of said lever to place the projected lateral end in the path of movement of the means for rotating said bolt and sliding said bolt and sleeve.

In testimony whereof I affix my signature.

WILLIAM C. SPEER.
